United States Patent Office.

EDWARD DOEN, OF NEW BRITAIN, CONNECTICUT.

Letters Patent No. 63,621, dated April 9, 1867.

IMPROVED CURTAIN FIXTURE.

The Schedule referred to in these Letters Patent and making part of the same.

TO ALL WHOM IT MAY CONCERN:

Be it known that I, EDWARD DOEN, of New Britain, county of Hartford, and State of Connecticut, have invented certain new and useful improvement in Curtain Brackets; and to enable others skilled in the art to make and use, I will proceed to describe the same by referring to the drawings, in which the same letters indicate like parts in each of the figures.

The nature of this improvement will be understood from the specification and drawings, the object of which is, first, to provide a knob (which usually has a pulley attached thereto) of such material as of itself will form a smooth surface without any extra labor, as glass, porcelain, &c., which will allow the cord to move freely over its surface, thereby saving the cost of labor and material for said pulley; and second, in providing a button prong or hook which projects one or both ways from its fastening-screw or pin, which serves to keep the curtain cord in place, or for a festoon hook (one or both) as may be desirable. The plate, with its ratchet, is much like those now in common use. In the accompanying drawings—

Figure 1 is a face view.

Figure 2 is a back side view.

Figure 3 is a sectional side view of figs. 1 and 2.

Figure 4 is a view of a two-prong knob.

a is the holding-plate, which is secured to the casing, having a ratchet, *b*, (formed on either side of the opening *c*,) or the equivalent device thereof for holding the button *d* in its proper place. *d* is a prong, hook, button, or knob, made of glass, porcelain, or other material, whose surface becomes smooth by the act of forming it, or by the inherent nature of the material from which it is formed. This hook or prong knob *d* is attached to a clutch, *e*, by means of a pin or bolt, *g*, by means of which the knob and clutch *d* are moved from one point to another. By lifting and pulling the knob the glass or porcelain prong or prongs of the knob *d* serve to protect the curtain cord from wearing or from becoming detached therefrom, and will also serve for the purpose of a festoon hook, thus greatly adding to the symmetrical appearance of the bracket, and rendering it at the same time more desirable and useful as an article of manufacture and trade.

I believe I have thus shown the nature, construction, and advantage of this improvement so as to enable others skilled in the art to make the same therefrom.

What I claim, therefore, and desire to secure by Letters Patent, is—

The combination of the glass or porcelain festoon prong knob *d*, with the ratchet or holding-plate *b*, as and for the purpose specified.

EDWARD DOEN. [SEAL.]
